UNITED STATES PATENT OFFICE

99,892

DESIGN FOR A COMBINED ELECTRIC CANDLE AND SUPPORT THEREFOR

Leo Pollock, New York, N. Y.

Application March 28, 1936, Serial No. 61,830

Term of patent 7 years

To all whom it may concern:

Be it known that Leo Pollock, a citizen of the United States, residing in New York city, in the county and State of New York, has invented a new, original, and ornamental Design for a Combined Electric Candle and Support Therefor, of which the following is a specification, reference being had to the accompanying drawing, forming a part thereof.

Fig. 1 is a front elevational view of a combined electric candle and support therefor; and
Fig. 2 is a side elevational view thereof.

I claim:

The ornamental design for a combined electric candle and support therefor, as shown.

LEO POLLOCK.
